UNITED STATES PATENT OFFICE.

GEORGE W. CHILLERS, OF ONTARIO, CALIFORNIA.

TIRE ARMOR.

Application filed June 11, 1925. Serial No. 36,472.

To all whom it may concern:

Be it known that I, GEORGE W. CHILLERS, a citizen of the United States, residing at Ontario, in the county of San Bernardino 5 and State of California, have invented certain new and useful Improvements in Tire Armors; and I do declare the following to be a full, clear, and exact description of the invention, such as will enable others skilled 10 in the art to which it appertains to make and use the same.

My invention relates to improvements in metallic tire armor and has for its object to provide a construction which is simple and 15 inexpensive, yet is exceptionally durable and advantageous, will make practically no noise even when running on hard pavements, and will be substantially proof against skidding.

With the foregoing in view, the invention 20 resides in the novel subject matter herein-after described and claimed, the description being supplemented by the accompanying drawing.

Figure 1 is a perspective view showing the 25 application of the armor to a tire casing.

Figure 2 is an enlarged sectional view through a portion of the armor cut in a circumferential direction.

Figure 3 is a plan view of one of the sections of the armor.

Figure 4 is a plan view of one of the metal straps which are secured to the outer sides of the channel-shaped sections of the armor and bent to form hooks for connecting said sections.

Figure 5 is an edge view partly in section, of the strap shown in Fig. 4.

In the drawing above briefly described, the numerals 1 designate a plurality of circumferentially extending, channel-shaped sections of the armor, each stamped from a single metal plate and each having an enlarged end 2 formed with a central notch 3, while at the opposite end, each section 1 is formed with a transverse slot 4. Obviously, the enlarged ends 2 of the numerous sections are adapted to receive the other ends of the next adjacent sections, as shown.

Secured upon the longitudinal, central 50 portion of each armor section 1, is a metal strap 5, one end of which is disposed at the inner edge of the slot 4, while its other end is received in the notch 3, the last named end having a thinned extension 6 which is bent 55 to form a hook bill, this bill of each section of the armor passing through the slot 4 of

the next adjacent section, as shown in Fig. 2. Moreover, it will be seen from this view that the hook bills 6 of the several armor sections lie against the inner sides of said sections and are of substantially negligible thickness, to overcome danger of injuring the tire casing around which the device is used. Preferably, one tapered rivet 7 is used to fasten each hook bill 6 and the contiguous end portion of the strap 5 to one end of each armor section 1, while a similar rivet 8 is used to secure the other end of the strap to the armor. By tapering the rivets in the manner shown, they will not loosen as the straps 5 and the outer ends of the rivets become worn.

Not only do the straps 5 assist in connecting the numerous sections of the armor, but they stiffen the central circumferential portions of said sections and jointly form substantially a continuous tread band, and this band assists materially in preventing skidding. Moreover, by having this band of substantially continuous form and free of any 80 large projections, the armor is almost noiseless, even when running on paved streets. In practice, the numerous sections of the armor are connected in a sufficiently loose manner to permit them to relatively move to 85 a slight extent as the tire yields, so that although such tire is effectively shod with metal, its resiliency is not impaired.

When applying the device, it is of course necessary to deflate the tire and the latter 90 is usually removed from the rim. When the device is applied however and the tire re-inflated, the tire casing snugly engages the armor and is held against any slipping or chafing thereon, by the internal pressure, 95 the armor being made a trifle smaller than the casing, in order that this snug fit may be obtained.

Excellent results are obtainable from the details disclosed and they are therefore preferably followed, but within the scope of the invention as claimed, slight modifications may be made.

I claim:

A metal tire armor comprising a plurality of circumferentially extending channel-shaped sections each enlarged at one end to receive the other end of the next adjacent section, the enlarged end of each section having a central notch while the other ends of said sections are formed with slots with which the notches register, and a plurality 105 110

of central circumferentially extending metal straps secured one to each of said sections, the strap of each section passing at one end through the notch of such section and having a hook bill which passes through the slot of the next adjacent section, the hook bills of the numerous sections lying flat

against the inner sides of said sections, said straps forming substantially a continuous tread and non-skid band around the armor. 10

In testimony whereof I have hereunto affixed my signature.

GEORGE W. CHILDERS.
